M. C. ROSENFELD,
BOTTLE WASHING BRUSH,
APPLICATION FILED FEB. 8, 1917.

1,228,140.

Patented May 29, 1917.

Inventor:

Max C. Rosenfeld
By his attorney, Charles D. Gooley

UNITED STATES PATENT OFFICE.

MAX C. ROSENFELD, OF BOSTON, MASSACHUSETTS.

BOTTLE-WASHING BRUSH.

1,228,140.

Specification of Letters Patent. Patented May 29, 1917.

Application filed February 8, 1917. Serial No. 147,469.

To all whom it may concern:

Be it known that I, MAX C. ROSENFELD, a citizen of the United States, residing at Boston, in the county of Suffolk and State 5 of Massachusetts, have invented new and useful Improvements in Bottle-Washing Brushes, of which the following is a specification.

This invention relates to an improved 10 brush for washing the insides of bottles, the same being particularly adapted to wash and clean the insides of carboys.

The invention consists in a brush constructed as hereinafter set forth in the specification and particularly as pointed out in 15 the claims.

Referring to the drawings,

Figure 1 is a sectional elevation of my 20 improved brush, a carboy being shown in connection therewith and broken away.

Fig. 2 is a sectional elevation similar to Fig. 1 illustrating the brush advanced into the carboy and contacting with the bottom thereof.

Fig. 3 is a detail section taken on line 25 3-3 of Fig. 1.

Fig. 4 is a detail section taken on line 4-4 of Fig. 1.

Fig. 5 is a perspective view of the wiper 30 tube.

Like numerals refer to like parts throughout the several views of the drawings.

In the drawings, 6 is a rubber tube slitted longitudinally thereof at 7 for a portion of 35 its length to form a plurality of wipers 8. 9 is a holder having a passage 10 extending therethrough and a recess 11 in its front end containing the unslotted portion of the rubber tube 6. 12 are scrubbers, each consisting of a rubber pad 13 which is fastened 40 to a spring metal shank 14, said shanks being clamped to the holder 9 by means of a clamp sleeve 15 which has a conical bore and is forced upon a conical portion 16 of the holder 9 by a pipe 17 which has screw-threaded engagement with the holder 9. The 45 holder 9 is also provided in its periphery with oppositely disposed grooves 18 in which the shanks 14 lie (see Fig. 3).

50 The metal shanks 14 project between two adjacent wipers 8 and are inclined toward the median axial line of the holder 9 at the forward end thereof, thus holding the tube 6 in the recess 11. A sleeve 19 encircles the 55 wipers 8 and the pads 13 when the brush is drawn into said sleeve as illustrated in

Fig. 1 and said sleeve is rotatably mounted in a bearing 20.

A bell-mouthed nozzle 21 is fastened to said bearing at its front end adjacent to the 60 sleeve 19 and is adapted to guide the wipers and the scrubbers into said sleeve when the brush is withdrawn from the bottle. The bell-mouthed nozzle 21 also serves as a rest and centering device for the bottle or carboy. 65

The pipe 17 is rotated by means of any suitable mechanism and the water for washing the bottles passes through said pipe and through the passage 10 in the holder 9 and 70 75 through the bore of the tube 6 into the bottle 22.

The general operation of the device hereinbefore specifically described is as follows: Assuming the parts to be in the relative positions illustrated in Fig. 1, with the neck of the bottle resting against the interior of the bell-mounted nozzle 21, the holder and brush, together with the pipe 17, are moved toward the left, Fig. 1, until they enter the 80 bottle 22. The water at this time is passing into the bottle through the pipe 17, holder 9 and tube 6. A rapid rotary motion is imparted to the pipe 17 which communicates a rotary motion to the holder 9 and 85 to the brush and also to the sleeve 19.

In Fig. 2 the brush is shown as advanced into the bottle in dotted lines, with the wipers extending outwardly to contact with the inner surface of the bottle, due to centrifugal force, and in full lines said wipers are shown as contacting with the bottom 23 of the bottle. The pads 13 serve to scrub the inside of the bottle and a portion of the bottom thereof and also the corners 24 as 90 95 seen in Fig. 2, while the wipers also assist in cleaning the interior of the bottle and especially the bottom inner surface thereof.

When the bottle is thoroughly washed, the brush is moved toward the right, Figs. 1 and 2, and is drawn into the sleeve 19 which continues rotating so long as the brush is rotated by the pipe 17, thus preventing injury to the wipers and to the scrubbers. 100

Having thus described my invention, what 105 I claim and desire by Letters Patent to secure is:

1. A bottle washing brush having, in combination, a rubber tube slitted longitudinally thereof for a portion of its length to 110 form a plurality of wipers, a holder for said tube having a passage extending longi-

tudinally therethrough with a recess in one end thereof containing the unslotted portion of said tube, and a scrubber consisting of a rubber pad and a spring metal shank, said shank being fastened to the periphery of said holder.

2. A bottle washing brush having, in combination, a rubber tube slotted longitudinally thereof for a portion of its length to 10 form a plurality of wipers, a holder for said tube having a passage extending longitudinally therethrough with a recess in one end thereof containing the unslotted portion of said tube, and a scrubber consisting of a 15 rubber pad and a spring metal shank, said shank being fastened to the periphery of said holder and projecting therebeyond and between two of said wipers.

3. A bottle washing brush having, in 20 combination, a rubber tube slotted longitudinally thereof for a portion of its length to form a plurality of wipers, a holder for said tube having longitudinal grooves in its periphery and a passage extending longitudinally therethrough with a recess in one 25 end thereof containing the unslotted portion of said tube, a scrubber consisting of a rubber pad and a spring metal shank, said holder having a conical portion, a sleeve 30 with a conical bore having engagement with the conical portion of said holder and a pipe having screw-threaded engagement with said holder and bearing against one end of said sleeve whereby said metal shanks may 35 be clamped to said holder within the longitudinal grooves provided in the periphery of said holder.

4. A bottle washing brush having, in combination, a rubber tube slotted longitudinally thereof for a portion of its length to 40 form a plurality of wipers, a holder for said tube having a passage extending longitudinally therethrough with a recess in one end thereof containing the unslotted portion of said tube, a scrubber consisting of a rubber 45 pad and a spring metal shank, said shank being fastened to the periphery of said holder, a rotary sleeve adapted to encircle said wipers and scrubber and a bearing within which said rotary sleeve is mounted. 50

5. A bottle washing brush having, in combination, a rubber tube slotted longitudinally thereof for a portion of its length to form a plurality of wipers, a holder for said tube having a passage extending longitudinally 55 therethrough with a recess in one end thereof containing the unslotted portion of said tube, a scrubber consisting of a rubber pad and a spring metal shank, said shank being fastened to the periphery of said holder, a 60 rotary sleeve adapted to encircle said wipers and scrubber, a bearing within which said rotary sleeve is mounted and a bell-mouthed nozzle fast to said bearing adjacent to said rotary sleeve and adapted to guide said 65 wipers and scrubber thereinto.

In testimony whereof I have hereunto set my hand in presence of two subscribing witnesses.

MAX C. ROSENFIELD.
